UNITED STATES PATENT OFFICE.

WILLIAM J. FRENCH, OF CARENCRO, LOUISIANA.

NUT-LOCK.

SPECIFICATION forming part of Letters Patent No. 234,766, dated November 23, 1880.

Application filed September 28, 1880. (No model.)

To all whom it may concern:

Be it known that I, WILLIAM J. FRENCH, of Carencro, in the parish of La Fayette and State of Louisiana, have invented a new and 5 Improved Nut-Lock, of which the following is a specification.

The object of this invention is to provide an improved device for securing nuts on railroad, bridge, and other bolts.

10 The invention consists of a recessed segmental washer, in combination with a segmental forked or pronged clip locking in with said washer.

Figure 1 is a sectional side elevation of the 15 device in position on a railroad fish-plate bolt. Fig. 2 is a front elevation of the same. Fig. 3 is a rear elevation of the washer portion of the device. Fig. 4 is a side elevation of the same. Fig. 5 is a rear elevation of the clip 20 portion of the device. Fig. 6 is a side elevation of the same. Fig. 7 is a front elevation of a modification of the washer portion of the device. Fig. 8 is a side elevation of the same.

Similar letters of reference indicate corresponding parts.

In the drawings, A represents a railroad-rail. B B are fish-plates provided with longitudinal central ribs, *a a*, on their outer faces; and C represents a bolt provided with a groove, 30 *b*, on the inner face of its head, corresponding with ribs *a* of a fish-plate, B.

D is the nut-lock, consisting of a circular washer, D', having a segment removed, as shown at *c*, having a rectangular recess, *d*, formed on its under side, as shown, and provided on its under side with a groove, *f*, corresponding with a rib, *a*, of a fish-plate, B, and having a central opening, *h*, to fit over the bolt C.

E represents the segmental forked or 40 pronged clip, designed to clasp the washer D' and fit against the straight edge thereof, so as to form, in combination therewith, a circular nut-lock. The inner fork, *g*, of the clip E is made to fit into the recess *d* of the washer D', 45 and is cut away in a semicircle, as shown at *i*, to fit against the shank of the bolt C, and is grooved, as shown at *k*, to fit over the rib *a* of a fish-plate, B. The outer fork, *l*, of said clip E is designed to rest on the flat upper face of 50 the washer D', and a broad slot, *m*, is made in it to enable it to embrace the nut F and hold

it firmly between its prongs *n n*, and on the inside of one of the prongs *n* a notch or shoulder, *o*, is formed to receive a corner of the nut F, and thereby hold clip E from being in any 55 way removed from its position, the nut F being backed up so as to be received by shoulder *o*.

The fish-plates B B being placed in position, the bolt C is passed through plates B 60 and rail A, the groove *b* of the said bolt C fitting on a rib, *a*, whereby said bolt C is prevented from turning when drawn up tight. The washer D' is then put over the end of the bolt C with the recess *D* upward and inward. The 65 nut F is then screwed on the end of the bolt C, and then the clip E is set in place from above, as shown in Figs. 1 and 2, the grooves *f k* of said lock D fitting over and upon the rib *a* of the fish-plate B, whereby said lock D is more 70 firmly held in position.

This construction of nut-lock is preferable for new work, or constructions in which the fish-plates and bolts are made with corresponding ribs *a* and grooves *b*; but for constructions 75 or work in which fish-plates or bolts of the usual style are used I employ a nut-lock devoid of grooves *f k*, and with a straight-edged flange, *p*, on the washer D', as shown in Figs. 7 and 8, so that the straight edge of said 80 flange *p* shall rest on the flange of the rail A, and thereby prevent said washer D' from turning.

This nut-lock D is preferably made of malleable iron, and is cheap and durable, and 85 most effectually accomplishes the purpose of holding a nut immovable.

Having thus described my invention, I claim as new and desire to secure by Letters Patent—

1. As an improved article of manufacture, a 90 nut-lock constructed substantially as herein shown and described, consisting of segmental washer D', provided with recess *d*, and clip E, provided with rectangular fork *g* and slotted fork *l*, as set forth.

2. The combination, with the washer D', provided with recess *d* and groove *f*, of the clip E, provided with forks *g l*, groove *k*, slot *m*, and notch or shoulder *o*, substantially as herein 100 shown and described.

3. In a nut-lock, the combination, with a seg-

mental washer, of a segmental forked or pronged clip clasping both sides of said washer, substantially as herein shown and described.

5. The combination, with the nut-lock D, provided with grooves *f k*, of the fish-plate B, provided with corresponding ribs *a*, substantially as herein shown and described.

5. The combination, with the ribbed fish-plates B B and grooved nut-lock D, of the bolt C, provided with head-groove *b*, and nut F, substantially as herein shown and described.

WILLIAM J. FRENCH.
